UNITED STATES PATENT OFFICE.

LUTHER L. SMITH, OF ANSONIA, CONNECTICUT.

APPARATUS FOR COATING WIRE.

SPECIFICATION forming part of Letters Patent No. 241,742, dated May 17, 1881.

Application filed December 22, 1880. (No model.)

To all whom it may concern:

Be it known that I, LUTHER L. SMITH, of Ansonia, Connecticut, have invented certain Improvements in Apparatus for Effecting the Uniform Electro-Deposition of Metal upon Coiled Wire, of which the following is a specification.

My improvements relate to apparatus adapted for employment in carrying out my process of electroplating coiled wire, one of the essential features of which consists in feeding the wire which is to be plated progressively through the electrolytic solution in a helical path, the several convolutions of the coil being partially or wholly submerged in the electrolytic solution, and being made to rotate upon a horizontal axis, whereby the motion of the wire in passing through the solution is substantially like that of the thread of a screw which is being inserted into or withdrawn from a stationary object.

My present invention consists in the combination, with an elongated tank of suitable width and depth, of a horizontal metallic roller, which extends longitudinally across the tank, and upon which the several convolutions of the coil of wire are hung, and which is connected with a dynamo-electric machine or other source of electricity. This roller may be provided with a spiral groove, or with parallel circumferential grooves, for the purpose of separating the several convolutions of the coil from each other; or, preferably, the roller may be smooth, and horizontal guiding-racks may be supported, respectively near the opposite sides of the tank, in position to cause the teeth of the racks to enter the spaces between the convolutions of the coil on either side of the roller, and thus separate them and cause them, by the rotation of the roller on which they are hung, to progress across the tank longitudinally in a helical path. The guiding-racks are made of wood, and are preferably arranged to float upon the surface of the plating-solution. Any number of coils of wire may be joined end to end, and thus successively plated by a continuous operation.

The accompanying drawings represent my improved apparatus as applied to the purpose of effecting the uniform electro-deposition of copper upon iron or steel wire.

In these drawings, Figure 1 is a top view of the apparatus, showing the tank provided upon each side with a row of anodes, and showing the guiding-racks upon each side, and the spirally-coiled wire hung upon the impelling-roller. Fig. 2 is a side elevation of the apparatus with a portion of the side of the tank broken out. Fig. 3 is a transverse vertical section through the line *x* *x* on Fig. 1. Fig. 4 is a longitudinal section of the device for joining the coils successively to each other.

The drawings represent a tank, *A*, of any desired length, near the sides of which two rows of anodes, *B*, are respectively suspended. Immediately adjoining the rows of anodes, on either side, are the wooden racks *C*, the teeth *c* of which project into the spaces between the convolutions *D* of the wire which is to be plated, and which, it will be seen, is hung upon the horizontal impelling-roller *E*, mounted in suitable bearings at the ends of the tank, and provided with the pulley *e* for receiving the belt *e'*, by which rotation is imparted to it. The impelling-roller *E* projects considerably beyond each end of the tank, the projection at one end, *a*, of the tank being for the purpose of holding the coil of wire preparatory to its introduction into the tank, and the projection at the opposite end, *a'*, being for the purpose of receiving the wire from the tank after it has been plated.

The operation of the apparatus is as follows: The coil of wire *D'* to be plated is hung upon the projecting end *E'* of the impelling-roller, and as the roller rotates one end of the coil is carried into the tank and guided downward through the successive notches of the guiding-rack upon one side of the roller, and upward through the corresponding notches of the guiding-rack upon the opposite side of the roller, and finally at the opposite end of the tank is carried out of the solution, and is received upon the projecting end *E''* of the roller. The impelling-roller is provided with suitable collars to prevent it from moving endwise in its bearings. In operation the coil of wire is gradually fed through the solution by the continued rotation of the roller at a rate of speed which is regulated with reference to such prolongation of the exposure of the wire to electrolytic action as may be necessary to obtain a deposit

of the desired thickness. When the coil has been nearly all fed into the tank, another coil may be hung upon the end E' of the impelling-roller, and the end of the second coil joined to 5 the end of the first coil, preferably by a thin metallic sleeve, G, in the opposite ends of which the ends of the wires are tightly fastened by riveting or otherwise. A piece of black thread or silk, G', is tied around the sleeve to indicate 10 the joint, and the earlier convolutions of the second coil thus follow the later convolutions of the first coil in their path through the solution. The operation of plating is thereafter continuous, the coils being hung upon the end 15 E' of the impelling-roller and joined to each other successively, as described.

By this mode of conducting a series of coils of wire through the electrolytic solution every 20 part of each coil is subjected successively to the same set of conditions, and variability in the energy with which electro-deposition is carried on in different parts of the solution will 25 make no difference in the thickness of the deposit upon different parts of the coils, because all parts of all the coils are successively carried through the same parts of the solution, and are exposed for equal periods to all the variable conditions which may exist in the different parts of the solution through which the 30 wire is conducted.

I do not herein claim the process of electro-plating wire which I have described, nor the product thereof—wire covered with a plating

of uniform thickness—as I intend to make this process and product the subjects of other applications for patents; but

What I do claim is—

1. In apparatus for effecting the uniform electro-deposition of metal upon coiled wire, a tank of any desired length, for containing the electrolytic solution, in which the several convolutions of the coil of wire are partially or wholly submerged, in combination with a horizontal roller upon which the several convolutions of the coil are hung, and guiding devices for separating the several convolutions of the coil from each other, and mechanism for causing the rotation of the roller, whereby the wire may be fed progressively through the solution in a helical path, substantially as described. 5

2. The tank A, adapted to contain an electrolytic solution, provided with the anodes B and the guiding-racks C, in combination with a horizontal roller, E, as and for the purpose set forth. 5

3. The tank A, adapted to contain an electrolytic solution, in combination with the roller E, projecting outward from the tank A at both ends, and mechanism for effecting the rotation of the roller E, substantially as and for the purpose set forth. 6
